UNITED STATES PATENT OFFICE.

OSCAR M. PANNIER, OF BEN AVON, AND LEON C. HAUER, OF PITTSBURGH, PENNSYLVANIA, ASSIGNORS TO PANNIER BROS. STAMP CO., OF PITTSBURGH, PENNSYLVANIA, A CORPORATION OF PENNSYLVANIA.

DIE HOLDER.

Application filed February 4, 1925. Serial No. 6,694.

Our invention consists of an improvement in die holders of the kind used for stamping metal. It has in view to provide such a device comprising a one-piece head having a terminal socket for the individual type or stamping dies, a slidable holder for holding and releasing the dies, a locking trigger therefor, and other features of improvement as hereinafter described.

10 The present invention is an improvement in that class of devices disclosed in the application of Leon C. Hauer, filed December 19, 1924, Serial No. 757,071.

15 In the drawings, showing one preferred embodiment of the invention:

Fig. 1 is a perspective view of the die holder and dies in position thereon;

Fig. 2 is a central vertical sectional view thereof;

20 Fig. 3 is a plan view, showing the holding slide retracted;

Fig. 4 is a perspective detail view of the holding slide;

25 Fig. 5 is a sectional detail view on the line V—V of Fig. 1;

Fig. 6 is an end view in elevation, showing a modified construction of the holding slide.

The main head or body 2 of the die holder 30 is generally rectangular in cross section and has a narrower holding portion 3 provided with a middle transverse hole 4 for insertion of a helve or handle. Said handle extension and its hole are disposed longitudinally or transversely of the main head 2, providing for swinging the dies against a hot metal surface by inserting a handle therein.

40 The main head portion 2 at its opposite end is provided with a rectangular socket 5, of sufficient proportions lengthwise and crosswise to receive a series of dies 6 by their widened bases snugly within it for positive seating against a hardened steel bearing bar 45 7. Said bar is made of a round section so that a corresponding round receiving hole may be easily bored or drilled clear through the head to receive it, as in the application above referred to. The middle bearing face 50 for the dies is planed off flat, as at 9, between the cylindrical ends, and the bar is held against rotation by one or more suitable keys or pins. In this manner, the flat

bearing seat 9 is positively maintained at right angles to the walls of the socket 5 55 for direct contact with the base of the dies 6, so as to absorb the thrust of the blows incident in using the dies in their intended way.

The several dies 6 are shouldered, as at 11, so as to provide a positive retaining abutment for engagement by the inner edge of the L-shaped slidable clamp 12, as in Fig. 2. Said clamp is slidably mounted along a suitably recessed corner portion of the base 65 2, and is provided with a dovetail or other suitably shaped retaining slide member 13, fitting within a corresponding longitudinal socket 14. The dovetail retaining strip 13 extends somewhat beyond the retaining shelf portion, together with an overlapping side extension 15, as in Fig. 4, so that, when it is thrust inwardly to holding position, as in Fig. 1, the entire slide occupies a position co-extensive with the length of the head 2. 75 The end portions 16 of head 2, defining the receiving cavity for the dies, form an integral portion of the head, so that, when the dies are placed in position and the slide 12 is thrust inwardly over the shoulders 11, 80 and against the reduced shanks of the dies 6, they will be firmly held and retained in position by the slide.

For the purpose of positively holding the slide either inwardly in closed position or 85 outwardly in open position for free insertion or removal of the dies 6, the inner face of dovetail strip 13 is provided with notches or ratchet cavities 17 and 17' respectively. These are of the form shown in Fig. 4, utilizing a combination of tapered and shouldered faces for engagement of the correspondingly shaped end 18 of a locking key 19. Said key 90 is preferably of dovetail or other suitable form in cross section for slidable mounting across the end of the head 2, as in Fig. 5. A cushioning spring 20 is interposed between its rear end and an inserted abutment 21, providing thrusting pressure to ensure interlocking engagement with the slidable 100 bar 12 in either position.

When open, as in Fig. 3, the slide is locked against further outward movement by key 19, but may be thrust inwardly without retracting the key, which will automatically recede, due to the tapered face of

socket 17'. When thrust clear in, as in Fig. 1, the key will move outwardly, engaging socket 17, and will hold the slide against accidental displacement or movement, until 5 the locking key is retracted. Said key and also the outer face of the slide bar are preferably knurled or otherwise roughened, as indicated, so as to facilitate engagement by the finger or thumb of the user for easy and 10 quick adjustment.

In Fig. 6, we show a modified construction of the device, in which the dies 6' may be of ordinary construction of uniform width from one end to the other, but provided with 15 a cross groove 22, as in standard die or type construction. The slide 12' in such case is completely within the body portion of the head 2', slidably mounted as just described, and held in the same way by 20 locking key 19, engaging corresponding sockets 16 and 17 in the inner upper face of the slide. Slide 12', however, in such construction is provided with a middle longitudinal key or spline 23, fitting inwardly in 25 a corresponding recess in the main head and extending across the several dies at the position of their several cross grooves 22, whereby to engage and fixedly hold them when inserted, and to release them when the slide 30 is withdrawn, as will be readily understood.

In either construction, it will be seen that the dies will be fixedly held in position and bear inwardly against the face of bar 7, and within the cavity 5, and are very firmly and 35 positively held. With either the shouldered engagement with the slide, or the grooved engagement with its inwardly extending rib, the same effect will be secured. The movement of the clamping bar in either case is 40 comparatively limited and restricted to the length of the die cavity, and the mounting of the holding slide bar and its locking key is comparatively simple, efficient, and durable under the strains of service.

45 The device may obviously be made in any desired size or proportions, is easily manip-

ulated, and readily used, either with or without the swinging handle.

What we claim is:

1. A holder for a removable die consisting 50 of a body member having a die socket, a slidably mounted clamping bar for the dies, and a locking device for holding the clamping bar open or closed.

2. A holder for a removable die consisting 55 of a body member having a die socket, a slidably mounted clamping bar for the dies, and a spring actuated locking device for holding the clamping bar open or closed.

3. A holder for a removable die consisting 60 of a body member having a die socket, a slidably mounted clamping bar for the dies having a portion adapted to engage a die when mounted in the socket, and a spring actuated locking device for holding the 65 clamping bar open or closed.

4. A holder for a removable die consisting 70 of a body member having a die socket, a slidably mounted holding bar for the dies provided with a plurality of locking sockets, and a spring actuated locking key adapted to engage either of said sockets to hold the bar in closed or open position respectively.

5. In combination with a die holder provided with a receiving socket, a slidably mounted retaining bar therefor having a portion adapted to engage the dies and a dovetail retaining slide member, and a 75 spring actuated locking key.

6. In combination with a die holder provided with a receiving socket, a slidably mounted retaining bar therefor having a portion adapted to engage the dies and a dovetail retaining slide member having a 80 pair of taper face shouldered sockets, and a spring actuated locking key mounted in the holder having a terminal adapted to engage one or the other of said sockets.

In testimony whereof we hereunto affix our signatures.

OSCAR M. PANNIER.
LEON C. HAUER.
